UNITED STATES PATENT OFFICE.

AUGUST F. KRAEMER, OF PROVIDENCE, RHODE ISLAND, ASSIGNOR TO LOUIS STERN COMPANY, OF PROVIDENCE, RHODE ISLAND, A CORPORATION OF RHODE ISLAND.

EXTENSION DEVICE FOR BRACELETS.

Application filed November 17, 1928. Serial No. 320,137.

This invention relates to improvements in an extension device for bracelets, more particularly watch bracelets for holding a wrist watch on the arm of the wearer; and the 5 object of the invention is to provide a plurality of sections hinged together to be folded one upon the other and to be unfolded or extended end to end to temporarily lengthen the bracelet so that it may be 10 passed over the hand of the wearer without detaching the bracelet parts one from the other.

A further object of the invention is the provision of simple and effective means 15 whereby the sections may be folded and nested one within the other and detachably secured in folded position to fit closely about the wrist of the wearer.

With these and other objects in view, the 20 invention consists of certain novel features of construction, as will be more fully described, and particularly pointed out in the appended claims.

In the accompanying drawings:

25 Fig. 1 is a perspective view showing my improved extension device as applied to parts of a bracelet and unfolded into extended position.

Fig. 2 is a top view showing the two end 30 channel members as being pivotally connected together by another section formed of a pair of spaced, side plates.

Fig. 3 is a sectional side elevation showing the three sections in extended position.

35 Fig. 4 is a sectional view showing the three sections as folded one within the other.

Fig. 5 is a perspective view of the attaching stud member removed from its channel section.

40 Fig. 6 shows the connecting bridge member as detached from its channel section.

Fig. 7 is a perspective view showing the side bars of one of the channel members with the top plate removed and the notches 45 in the side bars into which the bridge member fits.

Fig. 8 is a perspective view of a top plate such as that used on the bracelet links, a plurality of which are employed for forming the top wall of the main channel member.

50 Fig. 9 is a section on line 9-9 of Fig. 7.

Fig. 10 is a section showing the U-shaped bridge member as positioned between the side walls or plate of the main channel section and set in the notches illustrated at 55 9-9 in Fig. 7.

Fig. 11 shows the top plate as soldered over the ends of the bridge member and secured to the edges of the side plates shown 60 in Fig. 7.

Fig. 12 shows the main channel member having all of the sections nesting therein and one within the other.

It is found in the construction of bracelets of this character particularly of the watch type of bracelet, desirable to permanently attach the ends of the bracelet parts to the opposite bails of a watch and connect an extension device between the opposite bracelet parts whereby the device may be unfolded to lengthen the bracelet to such an extent that it may be readily passed over the hand of the wearer without completely disconnecting the bracelet parts from each other; and to accomplish this in a simple and effective way, I have formed the extension device in three parts, two elongated end channel members pivotally connected by a pair of spaced side plates, the side 65 plates being pivoted inside of the main channel section and to the outside of the other channel section whereby the side plate sections may nest within the main channel section and the other channel section nest between the side plates of the side plate sections thereby providing a very compact and 70 neat construction when folded by which construction a bridge member is supported between the side walls of one of the sections 75 and a connecting stud supported from the bottom wall of the other channel section to snap over the edge of this bridge member and so detachably connect the whole together; and the following is a detailed description of the present embodiment of my 80 invention and showing one means by which these advantageous results may be accomplished:

With reference to the drawings, 10 designates the main channel section which is formed of two side plates 11 along the outer edges of which are soldered a plurality of section cover plates 12 of a size, shape and

design of the bracelet links carrying the intricate decorations of these links, whereby this elongated main channel member has the appearance of being formed of a plurality 5 of separate links 13 like the rest of the bracelet parts 14.

I have also provided a second channel section 15 which is connected to the main channel by a section formed of a pair of spaced 10 side plates 16 which plates are pivoted at one end at 17 to the main channel member and at its opposite end 18 to the second channel member 15. This second channel member 15 is provided with a bottom wall 15 19 into which is riveted a fastening stud member 20 having a T-shaped head 21.

A fastening bridge or latch member 22 preferably formed in U-shape is provided with reduced laterally-extending end portions 23 to fit into notches 24 in the side plates of the main channel section to be soldered therein flush with the upper edge of these side plates and the loop of the U to extend down between these side plates, as 25 best illustrated in Fig. 12, whereby when the sections are folded one within the other the stud or catch 20 of the channel member 15 is caused to snap over the edge 24 of this bridge member 22, as best shown in Fig. 4, 30 to releasably retain these sections in nested or folded relation.

To one end 26 of the main channel section the bracelet part 14 is connected, while to the pivot 26 at the opposite end of the second channel section 15 the other part 14 of the bracelet is connected, whereby the unfolding of the extension device temporarily extends the operating length of the bracelet 40 to be readily passed over the hand of the wearer and when folded shortens the bracelet so as to fit snugly about the wrist of the wearer to firmly retain the watch in position on the wearer's arm.

My improved device is very simple and 45 practical in construction and is effective in its operation and by its use the length of the bracelet may be sufficiently extended to permit it to pass freely over the hand of the wearer.

The foregoing description is directed 50 solely towards the construction illustrated, but I desire it to be understood that I reserve the privilege of resorting to all the mechanical changes to which the device is susceptible, the invention being defined and

limited only by the terms of the appended claims.

I claim:

1. In a bracelet, an extension device comprising two channel-shaped sections pivotally connected together by a pair of side plates, said plates to nest inside of one channel section and the other channel to nest between said side plates, one of said channel sections having a U-shaped latch member supported on its side walls and the other of said channel sections having a cooperating catch member arranged to snap into engagement with said latch member to releasably retain the sections in folded position. 60 65 70

2. In a bracelet, an extension device comprising two channel-shaped sections pivotally connected together by a pair of side plates, said plates to nest inside of one channel section and the other channel to nest 75 between said plates, one of said channel sections having a latch member rigidly secured thereto and positioned between said side plates, and the other of said channel sections having a cooperating catch member 80 arranged to snap into engagement with said latch member to releasably retain the sections in folded position.

3. In a bracelet, an extension device comprising a plurality of end sections pivotally 85 connected together by a pair of side plates, said side plates nesting inside one end section and the other end section nesting between said side plates, one of said end sections having a latch member rigidly fixed 90 thereto and positioned between its side walls, and the other of said end sections having a rigidly fixed cooperating catch member arranged to snap into engagement with said latch member to releasably retain the 95 sections in folded position.

4. In a bracelet, an extension device comprising a plurality of arcuate end sections pivotally connected together by a pair of side plates, said side plates nesting inside 100 one end section and the other end section nesting between said side plates, one of said end sections having a latch member rigidly fixed to its side walls, and the other of said end sections having a rigidly fixed cooperating catch member arranged to snap into engagement with said latch member to releasably retain the sections in folded position. 105

In testimony whereof I affix my signature.
AUGUST F. KRAEMER.
